VEHICLE LIFTING DEVICE

Filed Feb. 27, 1920

UNITED STATES PATENT OFFICE.

EDWARD J. BECKER AND REMIG F. STOESER, OF CINCINNATI, OHIO.

VEHICLE LIFTING DEVICE.

Application filed February 27, 1920. Serial No. 361,870.

To all whom it may concern:

Be it known that we, EDWARD J. BECKER and REMIG F. STOESER, citizens of the United States, residing at Cincinnati, in the county 5 of Hamilton and State of Ohio, have invented certain new and useful Improvements in Vehicle Lifting Devices, of which the following is a specification.

Our invention relates to improvements in 10 hoisting devices, and more particularly to those used for lifting motor vehicles and the like, and for securely holding the vehicle in its lifted position.

The objects of our improvements are to 15 provide for lifting any one of a number of different sized vehicles, of varying design and construction in their running gear, with a minimum of care in adjustment of the device and without excessive labor in the 20 actual lifting operation, and to hold the vehicle securely in its lifted position so that it will not be displaced therefrom, as by collision of other vehicles therewith. A further object is to provide for bringing the 25 device into a compact condition for storage or transportation, or from that condition into condition for use as aforesaid, without the need of much care or skill in adjusting or placing the various 30 parts of the device. Other objects, among which is that of constructing the device as simply and inexpensively as is consistent with its purposed use, will appear in the course of the ensuing description.

We attain these objects by the device illustrated, for example, in the accompanying drawing, in which—

Figure 1 is a plan view of the device, adjusted to its operative position under a 40 vehicle, the necessarily shown parts of the latter being indicated by dotted lines;

Fig. 2 is a corresponding side elevation of the device with the vehicle elevated thereby and indicated as in Fig. 1;

Fig. 3 is a plan view of the device in folded condition;

Fig. 4 is an enlarged perspective view of the front-end parts of the device, in unfolded and operative condition.

Fig. 5 is a partial vertical lengthwise section of said front-end part on a plane corresponding to the line 5—5 of Fig. 4; and

Fig. 6 is a perspective view on the scale of Fig. 4, of rear-corner parts of the device, 55 in unfolded and operative condition.

In general, the device is an elongated

rectangular frame to engage under the front and rear axles of the vehicle, with suitable hoisting means to raise the frame with the vehicle thus supported thereon, and preferably 60 with means to stabilize the device after the lifting has been accomplished.

As exemplified herein, the elongated frame comprises the side bars 1 and 2 at left and right, respectively, each made of a 65 channel with its web vertical and its flanges extending in toward the middle of the frame. Attached to the rear-end part of each channel 1 and 2 is a respective hook-shaped section 3 or 4, made of an angle-bar 70 with an upright flange riveted to the side-bar channel web and the other flange extending under and riveted to the bottom flange of the channel. This angle-bar inclines downwardly and rearwardly from this 75 attachment and is then curved upwardly and forwardly, bringing its transverse flange to the top. The upright flange of the angle is cut away leaving this end of the section pointed, and the transverse flange 80 thus brought to the top, is bent down onto the cut edge; the proportions of these parts being so that this bent-down flange lies about horizontal slightly below the plane of the upper flange of the side-bar 1 or 2, and 85 so that a recess 5 is thus left under this pointed end of the section 3 or 4, opening upwardly forwardly of said end. The rear section 6 or 7 is a channel like the main side-bar 1 or 2, with its web upright and 90 its flanges extending inwardly of the frame, but with its lower flange severed from its web back a sufficient distance from the front end of the section and bent down and riveted to the transverse flange of the hook- 95 section where it curves upwardly; while the web of this channel is riveted to the upright flange of this hook section 3 or 4, as the case may be, and the top flange of this channel 6 or 7 is riveted to the bent-down 100 transverse angle of the hook-section 3 or 4. Preferably, the webs of the channels 1 or 2, and 6 or 7, are cut obliquely, the former with its point at the bottom and the latter with its point at the top; thus having ample 105 bearing on the hook-section upright angles where these webs are riveted thereto, but leaving the recess 5 unobstructed, with the nose 8, formed by the riveted-together flanges of the sections 3 or 4 and 6 or 7, 110 extending forwardly thereover behind the entrance thereto. To accomplish this ar-

angement of the parts while keeping the main side-bars 1 or 2 alined with the rear sections 6 or 7, the hook sections 3 and 4 have a slight compound bend in a transverse plane (Figs. 1 and 3).

The rear end of the frame is a strut 9 comprising a tube 10 with a bar 11 entering it and with a head 12 around the entrance, having a set-screw 13 to clamp the bar. Forks 14 and 15 are mounted on the free opposite ends of the tube 10 and bar 11, respectively, with their members about horizontal and entering between the flanges of the rear sections 6 and 7, respectively, and pivoted thereto by pins 16 passed upright through the members and flanges and preferably riveted or headed at their upper and lower ends. Latch hooks 17 are also pivoted on these pins just above the lower members of the respective forks 14 and 15, each having a lug 18 toward the outside of the frame as the hook is swung rearwardly, and having a short handle 19 continued out from the hook location.

The rear legs 20 are channels with their flanges inward, and have hinges 21 at their upper forward corners attached to the rear sections 6 and 7 on the bottoms thereof and far enough forward to have the rear sides 30 of the legs 20 about even with the rear ends of the sections 6 and 7 when the legs are swung down into upright position with the leg tops engaging up against the section bottoms. Hasps 22, fixed inside the channel 35 legs 20, extend past their upper ends, with openings that receive the lugs of the respective hooks 17 when the hasps have passed up through registering openings in the lower flanges of the sections 6 and 7 and the lower members of the respective forks 14 40 and 15, as the legs 20 are swung to their upright positions. The hooks 17 thus fasten the legs 20 in these positions, and the hasps 22, through the registering openings, lock 45 the strut 9 substantially at right angles to the frame side elements which it connects. To permit the lower members of the forks 14 and 15 to pass outward, the webs of the rear sections 6 and 7 are recessed at their 50 rear ends; and the upper fork members are cut away to an approximately triangular shape to clear these webs which are not cut away above. Each leg 20 has in its front flange, near its lower end, an aperture 23; 55 and latch bars 24 are mounted on the tops of the bottom flanges of the sections 6 and 7 to slide lengthwise thereof, each having a hook 25 extending down through a longitudinal slot in the respective supporting flange, 60 with an inclined face adapting it to slip into the leg aperture 23 as the leg 20 is swung forwardly and upwardly against the bottom of the section 6 or 7, and to hook under an edge of the aperture, holding the leg in its 65 folded position. Springs 26 mounted on

the webs of the sections 6 and 7 engage in apertures in the latch bars 24 to effect this latching engagement and to yield and permit manual unlatching.

A short distance back from the front end 70 of each main side-bar 1 or 2, the respective front leg 20' is mounted to swing down forwardly on its hinge 21', the same as the rear legs, and like them, having a latch bar 24 on the bottom flange of the side-bar 1 or 2, with its hook 25 engaging through the leg aperture 23' under the action of its spring 26'. To fasten these front legs 20' upright, bolts 27 slide down in guides 28 fixed to the outer sides of the respective side-bars 1 and 2 and enter sockets 29 on the outer sides of the legs 20' at their tops.

The front end of the frame is a yoke 30 comprising a channel with its flanges downward and with its web end-parts pivoted to 85 the under sides of the bottom flanges of the side-bars 1 and 2 by pins 31 passed upright through the web and both flanges of the bars 1 and 2. Latch hooks 17' are also pivoted on these pins just above the lower 90 flanges of the bars 1 and 2, each having a lug 18' toward the outside of the frame when the hook is swung forwardly, being like the hook 17 at the rear end of the device, before described, with their handles 19'. 95

The wheel forks 32 have the wheels 33 between their members, journaled on pins 34 in the members near the lower free ends thereof; and the top junction part of the fork lies up inside the channel of the yoke 100 30, near the respective end thereof, in such position that when the fork extends down the wheel 33 is presented for rolling the entire device lengthwise. The upper inner corner of each fork 32 has the hinge 35 connecting it to the under side of the yoke channel web to permit the fork and wheel to be swung laterally inwardly and upwardly close to the bottom of the yoke, as shown by the dotted lines in Fig. 4. Near the upper outer 105 corner of this fork, an ear 36 projects up, and the web of the channel of the yoke 30 and the lower flanges of the side-bar 1 or 2 have openings that register when the parts are swung substantially at right angles to 110 each other, so that the respective ear 36 projects up through the openings upon swinging the wheel fork 32 to upright position, and, the latch hook 17' having its lug 18' engaged in the ear, the fork and the frame 115 sides and yoke are all locked in their open operative positions.

Midway of its length the yoke channel has a journal-opening through its web; and an arch-bar 37 is riveted to the top of the 125 yoke by its feet 38 at opposite sides of the opening, and has a similar opening in its transverse top 39, in upright alinement with the opening in the yoke web. The ratchet-disk 40 has its teeth 41 on its upper circular 130

face, said teeth being relatively positioned like the teeth on a crown gear, and has its short lower hub projection 42 in the web opening and the upper-end part of its longer upper hub projection 43 in the arch-bar opening, this disk resting on the top of the yoke. The ratchet-bar 44 has a middle opening receiving the ratchet-disk hub-projection 43, with a collar 45 around this projection 5 spacing the bar down from the arch-bar top, and a washer 46 around this projection 10 spacing the bar up from the ratchet-disk teeth 41, so that this bar may thus swing in a transverse plane above and coaxial with the disk 40. The pawl-yoke 47 lies across 15 the top of the ratchet-bar 44 in front of the collar 45 and has its side members extending back and flanking the bar 44 and pivoted to the rear-end part thereof by a transverse pin 20 48. A U-shaped wire spring 49 has the rear end parts of its legs 50 coiled around lateral projections of the pivot pin 48 and bent under the adjacent parts of the ratchet-bar 44, while the front transverse part of this spring 25 49 bears down on the top of the pawl-yoke 47 in front of the collar 45. The middle of the pawl-yoke 47 has fixed on its lower side the pawl 51 projecting down against the ratchet-disk teeth 41. The front-end 30 30 part of the ratchet-bar 44 is forked, with a transverse pin 52 through its fork-members; and a handle-bar 53 has a forked end to slip between the ratchet-bar fork-members and straddle the pin 52, so that this handle-bar 35 35 may swing up and down on the pin to make it convenient to the reach of the operator, but will bind between the ratchet-bar fork-members for swinging the ratchet-bar in alternate transverse directions, thus turning 40 40 the ratchet-disk 40 in its bearings in the yoke 30 and arch-bar 37 by means of the pawl 51 riding freely over the teeth 41 one way, and engaging the teeth the other way, under the control of the spring 49.

45 The hub of the ratchet-disk 40 has a square opening entirely through it axially. The jack-screw 54 has the square upwardly projecting shank 55 slipped into this square opening, and this screw 54 is threaded into the base 56. The bearing-head 57 also has a square opening through it axially, and is slipped onto this square shank 55 down against a transverse bearing-pin 58 which is passed through either one of a plurality of 55 55 openings 59 transversely through the shank 55, before the shank is passed up through the ratchet-disk hub.

By having this bearing-head 57 thus adapted to be fixed at various heights on 60 the screw 54, quick adjustment of the jack device is facilitated in situations where the jack device might have to rest on a surface considerably lower than that supporting the wheels 33.

65 Any of the various well known jack con-

structions may readily be adapted for use with our invention, as will be understood.

The front-end yoke 30 of the frame is made short enough to permit the front end to pass between the wheel mountings of the 70 narrowest vehicle to be lifted; but the rear end of the frame may be adjusted by means of its telescoping arrangement of its tube 10 and bar 11, held at any desired adjustment within a considerable range by the set 75 screw 13. This rear adjustment of the frame width is preferable because of the wide variation in the design of various rear-axle constructions on the vehicles to be lifted. By this means, the frame bars can be 80 brought between the differential casing A (Fig. 1) at the middle, and the more or less extended rear-wheel mountings, brake-constructions, and the like, at the respective sides, on the different vehicles. 85

Many vehicles have brace-rods B (Fig. 2) running from their differential casings A out to the end parts of the axles on the under sides thereof. These rods are tension members only, and do not have the strength, as 90 beams, to receive the weight of the rear parts of the vehicle, as they would if permitted to bear on the frame-sides of our device. Hence the recesses 5 formed in the inserted sections 3 and 4, with the noses 8 extending 95 forwardly thereover; the latter directly receiving the amply strong main axle part C of the vehicle, and the brace-rod B occupying the recess 5 of the respective section 3 or 4, free of contact with any part that 100 would bend or otherwise injure it. These recesses 5 are preferably made amply large so that the noses 8 can project any required distance forwardly of them to engage under the axle part C in accordance with the height 105 of this part from the ground or floor, as will be understood from the ensuing description of the mode of use of the device.

Supposing the device to be folded as in Fig. 3, it is unfolded into its rectangular 110 condition and the rear legs 20 are dropped to upright position and they and the rear corners of the frame are locked together by the hooks 17, as before described. The wheel-forks 32 are dropped to upright position, 115 and they and the front corners of the frame are similarly locked together by the hooks 17'. These forks 32 are shorter than the rear legs 20, so that the device inclines downwardly forwardly, with its front end 120 supported on its wheels 33. It is thus wheeled forwardly under the vehicle from the rear thereof until the top of the frame engages under the rear axle C. The rear legs 20, which, during the wheeling, were 125 lifted from the ground or floor, will now rest on the ground or floor. The jack-screw 54, screwed down in its base 56, is now brought under the front of the frame, with its bearing-head 57 adjusted to the proper 130

height, and the top of the screw is inserted up through the ratchet-disk hub. Then the handle-bar 53 is applied as before described, and the ratchet is worked to turn the screw 54 in the base 56 in the direction to raise the front end of the device, which, upon engagement of the top of the frame with the vehicle front-axle D, will raise the front end of the vehicle; the rear end beginning 10 to be raised as soon as the ratcheting is begun, by virtue of the entire device swinging upward with the bottoms of its rear legs 20 as the fulcrum. When the front end has been raised far enough to permit the front 15 legs 20' to be swung down, these are brought into this position and locked by the bolts 27. The jack-screw 54 may now be screwed down in its base 56 by means of the handle-bar and ratchet, allowing the front of the vehicle to be supported by the front legs 20'; and if desired, this screwing down may be continued, permitting the jack-screw and its base 56 and bearing-head 57 to be removed from the rest of the device. This 25 permits these parts to be used on any one of several devices hoisting and holding as many vehicles; being very useful in this respect, especially in garages where many vehicles are cared for. Likewise with the 30 removable handle-bar 53, which would be an obstruction if permanently attached to the device.

With the vehicle thus supported on the four legs 20 and 20', which are rigidly locked 35 in their upright supporting positions, it cannot be pushed from its elevated position by collision of other heavy objects, such as running vehicles, as frequently may occur in garages or elsewhere. Between these 40 legs there are no low-hanging obstructions, so that free access is permitted for repairing, adjusting or cleaning the under parts of the vehicle. This simplicity of construction and arrangement is not accompanied 45 with any disadvantage in the hoisting operation; the lifting being all accomplished with a single jack device, and the rear of the vehicle being lifted thereby at a great mechanical advantage, since the entire frame 50 acts as a long lever of the second order. Also, this lever action is realized to some extent in lifting the front part, since the jack device is some distance forward from the bearing of the front axle D on the frame, 55 and, as is well known, the center of gravity of the vehicle is almost invariably to the rear of this front axle. The frame is made long enough to receive vehicles of the greatest length of wheel-base, and as the front 60 axle D may rest at any point simply on the frame top, and the rear axle without brace-rods B may rest likewise, while the recesses 5 and noses 8 are long enough to accommodate brace-rod rear axles at any practical 65 height relative to the rear legs 20, as before

described, there is no necessity of any specially adjustable bearing means at the top of the device to receive the axles of vehicles of different lengths of wheel-base. This greatly simplifies the application of the device to the vehicle. 70

The simultaneous locking of the rear legs 20 and frame rear corners, and of the wheel-forks 32 and frame front corners, and the unlocking of these parts in the same way, 75 facilitates the setting-up and taking down of the device. The compact folding of all of the legs and of the wheel mountings of the device, and the folding of the entire frame into a long, narrow condition, permits the device to be stored and shipped readily; for instance, it can be placed upright in a corner of the garage or other room when not in use, and in shipping, requires no special crate and the shipping expense is much 80 lower than for such a device in its extended operative condition.

We prefer the special interchangeable jack device herein described; but it is practicable to supply the device for use with 90 any ordinary vehicle jack, which may be placed under the front yoke. The special jack, with its shank or screw upper-part 55 through the ratchet-disk hub, has an advantage in that the device and vehicle are 95 prevented from being displaced if a collision of another vehicle or the like occur while the hoisting is being done, before the stabilizing front legs 20' are swung down and locked. 100

Other variations may occur; as, for instance, the jack device may be made non-detachable, and its handle bar may be permanently mounted thereon, and the wheel mountings and the rear legs may be 105 permanently secured in extended operative condition. The front legs 20' may be eliminated, relying on the three-legged support of the rear legs and jack device; and the entire device may be constructed to remain 110 permanently in extended operative condition. Any one or all of these variations may occur in a single example, as well as any one or several of many other variations in the details of construction and arrangement, with corresponding advantages or 115 disadvantages accordingly as conditions of use or considerations of expense of construction may dictate, or to meet the desires of individual users; it being our intent that any of these modified devices be secured to us if within the scope of our invention as 120 claimed herein. Thus, while the device is herein exemplified as one for application to the vehicle from the rear end thereof, many 125 vehicles permit of the insertion of this or a substantially similar device from the front end, and elevation at the rear end, with the advantage of lifting the heavier front end with the greater mechanical advantage. 130

Obviously, the inserted hook sections 3 and 4 may be omitted if the device be designed for use only on vehicles not requiring these provisions; or these details may be reversed 5 or otherwise modified to suit special conditions.

One mode of use to which our invention is adapted is the leaving of it in operative condition on the garage floor and running the 10 vehicle, either forwardly or backwardly as the case may be under varying conditions as just alluded to, over the device until in position to be lifted thereby. This is advantageous especially in small private 15 garages, where the extended device is no obstruction between uses, because the vehicle may thus be elevated at each storage thereof, as over night, relieving the tires of the pressure of the vehicle while out of use. 20 The ease with which this is accomplished with the single jack device operating at the marked mechanical advantage before described, makes the device especially suitable for this kind of use. 25 These possible adaptations and the susceptibility of our device to modifications under various conditions make it apparent that the specific example is herein disclosed with those contingencies in view, and therefore, 30 while certain constructional details are deemed preferable in connection with our invention, and we have shown and described these rather specifically in thus elucidating the construction and use of our 35 invention, as is required, we do not wish to be understood as being limited to such precise showing and description, but having thus fully described our invention, what we claim as new and desire to secure by Letters Patent is:

1. A vehicle-lifting device comprising a structure to be raised and lowered, laterally spaced fulcrum means connected solely to said structure near one end of said structure, holding said structure at a predetermined height, and lifting means connected solely to said structure near the opposite end of said structure and confined to the middle of the structure, whereby said 45 fulcrum means and said lifting means constitute a three-point support for the structure, said structure being adapted to receive the front and rear axles of the vehicle between said fulcrum and said lifting 50 means.

2. A vehicle-lifting device comprising a frame having its parts hinged together to fold out of operative condition, a fulcrum member hinged to said frame near one end 55 thereof to fold out of operative condition, and means to simultaneously lock said frame and fulcrum member in their operative conditions.

3. A vehicle-lifting device comprising an 60 element having a fulcrum near one end hold-

ing said element at a predetermined height, lifting means near the other end of said element, rotary supporting means, and a mounting for said rotary supporting means connected to said element near said lifting 70 means.

4. A vehicle-lifting device comprising an element having a fulcrum near one end, lifting means near the other end of said element, rotary supporting means, and a 75 mounting for said rotary supporting means hinged to said element near said lifting means, to fold out of operative position.

5. A vehicle-lifting device comprising an element having a fulcrum near one end, 80 lifting means near the other end of said element, rotary supporting means, a mounting for said rotary supporting means hinged to said element near said lifting means, to be folded out of operative condition, and 85 means to lock said mounting of said rotary supporting means in unfolded operative condition.

6. A vehicle-lifting device comprising a frame having its parts hinged together to 90 fold out of operative condition, a fulcrum near one end of said frame, lifting means near the other end of said frame, rotary supporting means, a mounting for said rotary supporting means hinged to said frame 95 near said lifting means, to fold out of operative condition, and means to simultaneously lock said frame and said mounting of said rotary supporting means in unfolded operative condition.

7. A vehicle-lifting device comprising a frame having its parts hinged together to fold out of operative condition, a fulcrum hinged to said frame near one end of said frame, to fold out of operative condition, 105 lifting means near the other end of said frame, rotary supporting means, a mounting for said rotary supporting means hinged to said frame near said lifting means, to fold out of operative condition, means 110 to simultaneously lock one end of said frame and said fulcrum in unfolded operative condition, and means to simultaneously lock the opposite end of said frame and said mounting of said rotary supporting means 115 in unfolded operative condition.

8. In a vehicle-lifting device, a frame comprising side-bars, a strut between adjacent end parts of said bars, and a yoke between the opposite end parts of said bars, 120 lifting means engaging said yoke near the middle of said yoke, rotary supporting means, mountings for said rotary supporting means connected to said frame near opposite ends of said yoke, and fulcrum members on said frame near opposite ends of 125 said strut.

9. A vehicle-lifting device comprising side-bars, a strut between adjacent end parts of said bars, a yoke between the opposite 130

end parts of said bars, lifting means engaging said yoke near the middle of said yoke, stabilizing elements near opposite ends of said yoke, adapted to be brought into operative condition after the lifting operation, and fulcrum members near opposite ends of said strut.

10. In a vehicle-lifting device, a frame comprising side-bars, a strut between adjacent end parts of said bars, and a yoke between the opposite end parts of said bars, lifting means engaging said yoke near the middle of said yoke, rotary supporting means, mountings for said rotary supporting means connected to said frame near opposite ends of said yoke, stabilizing elements hinged to said frame near opposite ends of said yoke, to be brought into operative condition after the lifting operation, and fulcrum members on said frame near opposite ends of said strut.

11. A vehicle-lifting device comprising side-bars, a strut pivoted to said bars between adjacent end parts of said bars, a yoke pivoted to said bars between opposite end parts of said bars, said strut and said yoke being adapted to swing on said bars substantially in the transverse plane of the device, lifting means engaging said yoke near the middle of said yoke and adapted to be displaced from its operative position relative to said yoke, rotary supporting means, mountings for said rotary supporting means pivoted to said yoke near opposite ends of said yoke to fold inwardly and upwardly toward said yoke, stabilizing elements pivoted to the respective side-bars near the respective rotary supporting means and adapted to fold upwardly toward the respective bars, and fulcrum members pivoted to said side-bars near opposite ends of said strut and adapted to fold upwardly toward the respective bars.

12. A vehicle-lifting device comprising side-bars, a strut pivoted to said bars between adjacent end parts of said bars, a yoke pivoted to said bars between opposite end parts of said bars, said strut and said yoke being adapted to swing on said bars substantially in the transverse plane of the device, lifting means engaging said yoke near the middle of said yoke and adapted to be displaced from its operative position relative to said yoke, rotary supporting means, mountings for said rotary supporting means pivoted to said yoke near opposite end parts of said yoke to fold inwardly and upwardly toward said yoke, stabilizing elements pivoted to the respective side-bars near the respective rotary supporting means and adapted to fold upwardly toward the respective bars, fulcrum members pivoted to said side-

bars near opposite ends of said strut, means for simultaneously locking said strut and the respective fulcrum members in their operative positions, and means to simultaneously lock said yoke and the respective mountings for the rotary supporting means in their operative positions.

13. A vehicle-lifting device comprising side-bars with upwardly opening recesses near adjacent end parts, a strut between said end parts of said bars, a yoke between the opposite end parts of said bars, lifting means engaging said yoke, and fulcrum members near opposite ends of said strut.

14. A vehicle-lifting device comprising an element having a fulcrum near one end, a yoke near the other end of said element, an arch-bar on top of said yoke, said arch-bar and said yoke having aligned openings, a ratchet element between said arch-bar and said yoke, journaled in said openings, a pawl element mounted to operatively engage said ratchet element, and a jack-screw operatively engaged by said ratchet element.

15. A vehicle-lifting device comprising a vehicle-engaging element with a recess and a nose projecting partly across said recess, and means for lifting said element.

16. A vehicle-lifting device comprising channel sections and a section formed of an angle-bar bent into hook shape with the entrance of the hook upward, said angle-bar having an upright flange fastened to the webs of the channel sections and a transverse flange fastened to the lower flange of one of the channel sections and to the upper flange of the other channel section, and means for lifting the structure thus constituted.

17. A vehicle-lifting device comprising a frame made up of side channels with their flanges extending inwardly of the frame toward each other, a strut made up of end forks pivoted between the top and bottom flanges of the channels, a tube on one of the forks and a bar on the other fork, secured in said tube, and lifting means connected with said frame.

18. A vehicle-lifting device comprising a frame made up of side channels with their flanges extending inwardly of the frame toward each other, a yoke made up of a channel with its flanges extending downwardly and its web pivoted to the lower flanges of said side channels near adjacent ends thereof, lifting means engaging with said yoke, and connecting and supporting means connected to said channels near their other ends.

EDWARD J. BECKER.
REMIG F. STOESER.
